UNITED STATES PATENT OFFICE.

JOHN F. ROSE-SOLEY, OF SAN FRANCISCO, CALIFORNIA.

DESIGN FOR A BELT.

SPECIFICATION forming part of Design No. 29,096, dated July 26, 1898.

Application filed July 16, 1897. Serial No. 644,847. Term of patent 14 years.

To all whom it may concern:

Be it known that I, JOHN F. ROSE-SOLEY, a subject of Her Majesty the Queen of Great Britain, residing at San Francisco, State of California, have invented and produced a new and useful Design for a Belt, of which the following is a specification, reference being had to the accompanying drawing, forming a part thereof.

10 The figure represents a perspective view of a belt embodying my design.

As shown in the drawing, the leading or material feature of my design consists of a flat band with unbroken and continuous end portions and a homogeneous intermediate braided portion of reduced width connecting with the said end portions by reversely-curved lines. The end portions A A' have sufficient length to give them prominence. These end portions are flat, and the portion between them, commencing at a point removed from the extremities of each of said ends, is di-

vided into a number of narrow strips *a*, which merge into the contiguous flat ends on curved lines *b*, the lines upon one side of the center of the belt curving in one direction and those at the opposite side of said center curving in a reverse direction. This gives an ornamental flat portion interposed between plain ends, the effect being increased from the fact that while the side edges of the end portions are straight and unbroken the edges of the braided portion have the appearance of being corrugated or fluted.

What I claim is—

15 The design for a belt substantially as shown and described.

In witness whereof I have hereunto set my hand.

JOHN F. ROSE-SOLEY.
